UNITED STATES PATENT OFFICE.

GILBERT L. CROWELL, JR., OF ARLINGTON, NEW JERSEY, ASSIGNOR TO
THE DOMINICK & HAFF, OF NEW YORK, N. Y.

DESIGN FOR A HANDLE FOR SPOONS, FORKS, OR SIMILAR ARTICLES.

SPECIFICATION forming part of Design No. 32,727, dated May 29, 1900.

Application filed May 4, 1900. Serial No. 15,547. Term of patent 7 years.

To all whom it may concern:

Be it known that I, GILBERT L. CROWELL, Jr., a citizen of the United States, residing at Arlington, in the county of Hudson and 5 State of New Jersey, have invented and produced a new and useful Design for Handles for Spoons, Forks, and Similar Articles, of which the following is a description, reference being had to the accompanying drawings, 10 which illustrate the design.

Figure 1 is a plan or elevation view of the front or obverse side of a spoon the handle of which embodies my design, the dotted lines showing how the handle may be applied 15 to a fork. Fig. 2 is a similar view of the reverse or rear side of the spoon and handle. Fig. 3 is a cross-section on the plane *a a* of Fig. 1.

The general outline of the handle is of the 20 spatulate, inclining to the pandurate order. Along the opposite edges of both sides of the handle and substantially parallel with such edges are lines of fluting or beading *A*, which terminate in scroll-like ornamentalations *B*, 25 which form the outline of the head of the handle and are similar on both its sides. This fluting as it approaches the head on the front side of the handle is somewhat interrupted by small scroll ends or tips *C*, and at the 30 union of the handle with the bowl of the spoon

the fluting upon the opposite edges of the front side diverges in equal curves and ends abruptly in the paw-like terminals *D*. On the reverse side of the handle the lines of fluting are continuous from its head to and 35 extending down upon the bowl, where they are divergently and then convergently curved to form a diamond-shaped figure *E*, ornamented with small scrolls and an urn-like tip. Also toward the head of the handle the 40 fluting is disposed to produce a Gothic appearance *F*. The surfaces between the lines of the fluting on both sides of the handle are preferably without ornamentation.

The essential features of this design consist of a handle for a spoon, fork, or similar article having a spatulate-pandurate-shaped outline or form and fluting or beading extending along the opposite edges on both sides of the handle and terminating at its head in 45 outline scroll ornamentation.

What is claimed as new is—

The design for the handle of a spoon, fork or other similar article, substantially as shown and described.

GILBERT L. CROWELL, JR. [L. S.]
